UNITED STATES PATENT OFFICE

NATHAN E. MERRILL, OF LONG BEACH, CALIFORNIA

APPARATUS FOR DISTILLING LIQUID HYDROCARBONS

Application filed January 30, 1926. Serial No. 84,807.

An object of my invention is to provide a shell construction through which the fluid hydrocarbons may be continuously run.

Another object is to provide an apparatus for treating fluid hydrocarbons which may be used as either a cracking or a straight distillation unit.

Further objects are to provide an apparatus of the character stated which is simpler and less expensive in construction and operation.

A feature of the invention is to provide a sectional shell unit giving easy access to the interior.

Another feature is to provide a sectional shell unit the various sections of which may be quickly replaced at small expense.

Still another object of my invention is to maintain the vapors under pressure in the still at or above the temperature of vaporization.

A still further object is to provide an apparatus of the character stated which may be used as a dehydrator.

Advantages of my apparatus are:—only a small amount of the treated fluid is exposed to the hazard of fire, and moisture in the fluid will not affect the operation.

Other objects, advantages and features of invention may appear from the accompanying drawings, the subjoined detailed description, and the appended claims.

In the drawings I have illustrated the preferred form of my invention but it may also be embodied in other forms, and in this application I desire to cover my invention in whatever form it may be embodied within the scope of my claims.

Fig. 1, is a longitudinal sectional view of my apparatus in operative position.

Fig. 2, is a sectional view on line 2—2

Fig. 1.

Fig. 3, is a sectional view on line 3—3 Fig. 1, looking downwardly.

Fig. 4, is a sectional view on line 3—3 Fig. 1, looking upwardly.

Fig. 5, is an enlarged fragmentary sectional view of the lower part of the still showing a type of check valve.

Referring more particularly to the draw-

ing, the shell still or unit 1, comprises a lower tubular section 2, an intermediate section 3, an upper section 4 and a cap 5. Each of the sections and the cap are flanged and riveted or bolted together, and each section may be removed for repairs without disturbing the entire unit.

A heating plate 6 closes the lower end of the section 2 and is riveted or bolted to said section, so that it may be removed when necessary. This plate may be concaved if desired for greater strength and heating surface.

The unit 1 is mounted on and rises from a furnace 7, and the section 2 extends thru the wall of the furnace so that the plate 6 is directly exposed to the heat. The furnace 7 may be of any well known construction the details of which form no part of this invention.

A conical wall 8 is provided in the section 2, and forms, with the plate 6, a heating chamber 9. A tube 10 extends upwardly from the chamber 9 to adjacent the upper end of the section 4, and the tube is open at the top to permit the passage of vapors and fluid as will be further described.

Baffle plates 11 are formed in a spiral on the outside of the tube 10 and spiral baffle plates 12 extend inwardly from the wall of the section 4 to coact with the plates 11. A wall 13 separates the sections 4 and 3 to form a heat exchanger 14 in the section 3.

The fluid to be acted upon flows from a reservoir (not shown) into heat exchangers 15, thence through a pipe 16 to a coil 17 in the heat exchanger 14. A valve 18 in the pipe 16 controls the flow therethrough. The reservoir is at such an elevation that the fluid flows by gravity into the exchanger 14, thus eliminating a pump. The coil 17 extends to a check valve 18 which projects through the wall 8 into the chamber 9. This valve may be of any suitable type, such as the ball check shown, which prevents the fluid under pressure in the chamber 9 from passing back into the coil 17. The fluid passes into the chamber 9 and rises in the tube 10 to a height regulated by the height of the reservoir. The furnace 7 raises the fluid in the chamber 9 to the

required temperature and liberates the vapors. These vapors pass upwardly in the tube 10, carrying a quantity of fluid therewith.

A baffle plate 19 is mounted in the top of the section 4, and perforations 20 therein are so arranged that the fluid ejected from the tube 10 will not pass therethrough but will be deflected downwardly on the baffle plates 11, 12, while the vapors pass through the perforations into the cap 5. As the fluid passes over the baffle plates 11, 12, it is thoroughly agitated, and the vapors trapped therein are liberated and pass upwardly along the spiral baffle and pass out into the cap 5. The hot fluid after it reaches the bottom of the baffles passes through holes 21 in the plate 13 into the heat exchanger 14, thus raising the temperature of the incoming fluid in the coil 17.

A pipe 22 leads the hot fluid from the exchanger 14 to the coils of a heat exchanger 23, and pipe 24 leads the hot fluid from these coils to the coils of the heat exchanger 15. Thus the hot fluid serves to operate three sets of heat exchangers i. e. 14, 23 and 15.

The vapors after passing into the cap 5 are conducted through a pipe 25 to a dephlegmator 26 which is of well known and standard construction. The vapors are partly condensed in the dephlegmator and the condensate passes through a pipe 27 to the drum of the heat exchanger 23 and the vapors pass out through the duct 28.

A steam coil 29 is provided in the lower part of the section 4, to control the vapors in the section 4.

The chamber 9 is made relatively small so that the quantity of fluid therein is quickly raised to the required temperature with a small expenditure of fuel in the furnace. The fluid and vapor rising therefrom are maintained under hydro-static pressure in the chamber 9, under the heat of vaporization, and such pressure is determined by the height of the tube 10, in which a constant flow of liquid and vapor is maintained. Water in the fluid will not hinder the operation of my device, since it merely passes off at the lower temperature before the vapors (which come off at a high temperature) start to form.

If desired an air coil may be placed in the chamber 9 to aerate a fluid such as asphalt for roofing purposes.

In a distilling or cracking process the operation is continuous; the fluid flows through the valve 18 into the chamber 9 as the fluid in said chamber is forced out of the tube 17 and this constant in-coming of fresh fluid causes an agitation and prevents settling of a residuum.

A quick operating valve may be inserted in the coil 17 so that only a small amount of fluid is exposed to the hazards of fire in the still.

I claim:

1. In an apparatus for distilling liquid hy-

drocarbons the combination of a sectional shell, adapted to be mounted on a furnace, a plate removably secured to the bottom of said shell, said shell and plate forming a chamber above said plate adapted to receive the liquid to be treated, said plate and chamber being within the furnace, a tube within the shell rising from said chamber through which the vapors and liquid pass, and means to conduct the vapors from said shell. 70

2. In an apparatus for distilling liquid hydrocarbons the combination of a sectional shell, adapted to be mounted on a furnace, a plate removably secured to the bottom of said shell, said shell and plate forming a chamber above said plate adapted to receive the liquid to be treated, said plate and chamber being within the furnace, a tube rising from said chamber through which the vapors and liquid pass, and means to conduct the vapors from said shell, and a plurality of superposed baffles in said shell over which the hot liquid passes after leaving the tube. 80

3. In an apparatus for distilling liquid hydrocarbons the combination of a sectional shell, adapted to be mounted on a furnace, a plate removably secured to the bottom of said shell, said shell and plate forming a chamber above said plate adapted to receive the liquid to be treated, said plate and chamber being within the furnace, a tube rising from said chamber within the shell through which the vapors and liquid pass, and means to conduct the vapors from said shell, and baffles in said shell over which the hot liquid passes, and a heat exchanger through which the incoming liquid passes and into which the hot liquid passes after passing over the baffles. 90

4. In an apparatus for distilling liquid hydrocarbons the combination of a shell, a plate removably secured to the bottom of said shell, a conical wall in said housing above said plate and covering the plate, and a tube in which liquid being distilled rises, said tube rising from said wall within the shell, means to heat said plate, and a plurality of superposed baffles in said shell over which the liquid passes. 105
